FURNACE

Orin Kelly, Columbus, Ohio

Application November 17, 1930, Serial No. 496,266

6 Claims. (Cl. 110—109)

My invention relates more particularly to furnaces of the self-stoking type.

One of my objects is to provide a construction of self-stoking furnace which will be highly suitable for the use of slack coal as the fuel to be burned therein, the tars in such coal having a tendency to bake.

Another object is to provide a construction of furnace of the type above referred to which will be highly suitable for domestic uses which requires the feeding of the fuel in relatively small amounts and the provision of low power feeding mechanism.

Another object is to provide a construction of furnace of the type above referred to and involving as an element thereof a plunger for feeding the coal, in which the "bunching" of the coal ahead of the plunger, with the consequent exertion of objectionable forces against the side walls of the trough in which the plunger operates is minimized and in which the power required for operating the plunger is reduced to the minimum.

Another object is to provide a construction of furnace of the type above referred to by which a small and regular feed of the coal may be effected.

Another object is to avoid the tendency of the coal when wet or dirty to pack or hang in the hopper from which the coal feeds to the feeder mechanism.

Another object is to provide a construction of furnace of the type above referred to in which not only is it possible to feed small quantities of coal and effect such feed regularly and uniformly, but it is also possible to vary the feed to feed larger or smaller quantities as desired.

Another object is to provide an effective seal against the escape of gases and smoke from the furnace in the event of the continuation of the operation of the feeding mechanism after the hopper from which the coal is fed to the feeding mechanism becomes exhausted.

Another object is to provide for the regular and uniform feeding of small quantities of coal without danger of imposing heavy loads or stresses on the mechanism should a relatively large lump of coal be encountered by the feed-device.

Another object is to provide a construction of furnace whereby the fire bed is rendered self-cleaning, even with the worst of clinker-forming coals, or as frequently happens, when tin cans, broken glass, crockery, and other non-combustible masses are thrown into the furnace,

Another object is to avoid the forcing of live coals into the ash pit by the stoking mechanism; thereby economizing in the use of fuel; and other objects are as will be manifest from the following description.

Referring to the accompanying drawings:

Figure 1 is a view in longitudinal sectional elevation of a furnace constructed in accordance with my invention, the section being taken on line 1—1 of Fig. 2 and viewed in the direction 5 of the arrow.

Figure 2 is a rear view of the furnace the furnace being viewed from the right-hand side of Fig. 1.

Figure 3 is a broken sectional view of the furnace of the preceding figures, the section being taken at the line 3—3 on Fig. 1 and viewed in the direction of the arrows.

Figure 4 is a broken plan sectional view taken at the line 4—4 on Fig. 1 and viewed in the direction of the arrows.

Figure 4^a is a broken plan view of one of the reciprocatory devices for feeding the fuel through the coking chamber.

Figure 4^b is a section taken at the line 4^b on Fig. 4^a and viewed in the direction of the arrows.

Figure 5 is a broken plan sectional view taken at the line 5—5 on Fig. 3 and viewed in the direction of the arrows.

Figure 6 is a broken section taken at the line 6—6 on Fig. 1 and viewed in the direction of the arrows with certain parts omitted.

Figure 7 is a broken section taken at the line 7—7 on Fig. 1 and viewed in the direction of the arrows also with certain parts omitted.

Figure 8 is a view in sectional elevation of a portion of the mechanism for operating the feed device; and

Figure 9, a plan section taken at the line 9—9 on Fig. 8 and viewed in the direction of the arrow.

In the following description of the construction shown that end of the furnace into which the fuel is introduced is termed the rear end of the furnace and its opposite end the front end thereof.

The particular illustrated construction of furnace, shown as a hot-air furnace, comprises hollow end heads 10 and 11, flue pipes 12 and 13 for the products of combustion communicating with the interiors of the heads 10 and 11, an arched member 14 interposed between the heads 10 and 11, a lower frame member 15 and a casing 16, for the circulation therethrough of the air to be heated, surrounding the above described parts in spaced relation thereto, the casing 16

containing an inlet 17 for the air to be heated and outlets 18 for the heated air.

The rear head 10, which rests at its sides on the frame 15, is provided with a horizontal partition 19 dividing the space within the head into upper and lower compartments 20 and 21, respectively, opposite side portions of this head being alined with the side walls 22 of the member 14, the forward wall of the head 10 at its lower portion being open as represented at 23 and the side wall of the compartment 20 containing outlets 24 for communication with a stack (not shown).

The front head 11, which also rests at its sides on the frame 15 contains a partition 25 which alines with the upper portion of the member 14 and divides the space within the head 11 into upper and lower compartments 26 and 27, respectively.

20 The flue pipes 12 connect at their opposite ends with the interior of the upper compartment 20 of the head 10 and the upper compartment 26 of the head 11, and the flue pipes 13, arranged at opposite sides of the furnace, connect at their opposite ends with the interiors of the lower compartment 21 of the head 10 and the upper compartment 26 of the head 11, the lower compartment 21 of the head 10 communicating at the opening 23 with the lower portion of the space within the member 14.

25 By the arrangement described a combustion chamber, indicated at 28 and comprising the heads 10 and 11 and the member 14, is provided, the products of combustion generated therein passing from this chamber rearwardly into the lower compartment 21 of the head 10 and thence upwardly, in divided streams, into the rear ends of the flue pipes 13 and forwardly in the latter into the compartment 26 of the head 11 from 30 which they pass rearwardly through the flue pipes 12 into the compartment 20 of the head 10 and then discharge to the stack.

35 The furnace shown comprises mechanical stoking means for feeding fuel, such as for example slack coal, and fed thereto as hereinafter described to the fire-bed, these stoking means also comprising the grate portion on which the fire-bed is supported.

40 The combined grate-forming and stoking mechanism shown comprises a series of stationary grate sections 29 extending entirely across, and forming the bottom of, the combustion chamber 28, these grate sections being spaced apart vertically and arranged in the form of steps as shown.

45 Interposed between adjacent ones of the stationary grate sections 29 are grate sections 30 mounted to be reciprocated lengthwise of the furnace and operating to advance the fire-bed toward the rear end of the furnace and replenishing the fire-bed with fuel delivered thereto at the front end of the furnace as hereinafter described.

50 The movable grate sections 30, together with a plunger 31 located directly above the uppermost stationary grate section 29, are rigidly connected together by brackets 32 and 33 and rods 34. The brackets 32 and 33 are duplicated at opposite sides of the furnace and each of the brackets 32 is provided on its underside with a rack 35, these racks meshing with gear-segments 36 rigid on the ends of a rock-shaft 37 having an arm 38 pivoted at 39 to one end of a link 40 the opposite end of which is pivotally connected to a crank pin 41 on a disk 42 rigid on a shaft 43 and actuated by the mechanism hereinafter described, the disk 42 containing a series of openings 42a disposed at

5 different distances from the shaft 43 to selectively receive the pin 41 for varying the throw of the link 40.

10 The furnace structure also comprises a plate 121 which extends across the rear end of the combustion chamber and is pivotally supported at its ends in yoke bearings 122 (one only of which is shown) extending inwardly from the side walls of the chamber 28, the plate 121 having a weight 123 extending to one side of the axis about which 15 the plate 121 is swingable. Located to the rear of the one of the grate sections 29 nearest the rear end of the furnace is a plate 124 which extends rearwardly beyond the rearward travel of the lowermost one of the reciprocable plate sections 30, but spaced from the rear wall of the combustion chamber 28, whereby an opening therebetween to the ash pit of the furnace represented at 125 is provided; the plate 121 and plate 124 being so relatively positioned, as shown, that 20 the plate 121 normally inclines downwardly in a forward direction under the action of the eccentrically disposed weight 123.

25 The ash pit represented at 125 preferably contains ash pans 126 shown as arranged in a series 30 extending from the front to the rear of the furnace, the rear and side walls of the ash pit preferably being provided with flanges 127 which overlap the rear edge of the rear pan and the side edges of each pan, adjacent ones of these pans 35 having hook shaped lips 128 which overlie the adjacent edges of the adjacent pans, thereby providing means for insuring the dropping of all of the ashes into the pans.

35 The top portion of the arch member 14 forms 35 the top and sides of a coking chamber 44, the bottom of which is formed of a series of alternating stationary and sliding sections 45 and 46, respectively, which are arranged in the form of steps but reach short of the forward end of the 40 furnace thereby to provide an opening 47 at the forward end of this coking chamber through which the coal to be consumed in the furnace and preliminarily heated by the heat generated in the fire-bed below it, discharges to the grate-forming and stoking mechanism above described.

45 The bottom of the coking chamber contains 50 openings therethrough through which the fine particles of coal may drop upon the hot fire-bed below. In the construction shown both of the fixed plate-sections 45 are slotted as represented at 46 to form the above referred to openings in the bottom of the coking chamber.

55 The sections 45, each of a length substantially equal to the width of the coking chamber as shown in Fig. 3, are grooved along their opposite edges as represented at 49 at which they are supported on ribs 50 extending inwardly from the sides of the coking chamber, these plates being provided along their longitudinal edges with upwardly extending flanges 51 forming guides for the sliding sections 46.

60 The upper one of the sliding sections 46 is formed of a pair of parallel bars 52 having shrouded rack portions 53 along their undersides 65 at their outer ends at which they project rearwardly through the rear wall of the casing 16, the bars 52 being connected together at their outer ends by a yoke 54. The inner ends of the bars 52 which extend between the flanges 51 are recessed along their opposing surfaces as represented at 55 and along their upper surfaces as represented at 56, whereby they present upwardly facing seats 57 from both ends of each of which shoulders 58 on the bars 52 project inwardly. The section 70

46 now being described also comprises a plate member 59 which spans the space between the bars 52. The plate 59 is recessed at its opposite ends as represented at 60 at which it receives the shoulder portions 58 of the bars 52, the underside of the plate 59 at its opposite edges being recessed lengthwise of the plate as represented at 61 at which the plate extends into the recesses 56 in the bars 52 and rests on the bottoms of these recesses.

10 The lower one of the sections 46 comprises parallel spaced apart bars 62 pivoted at their rear ends, as represented at 63, to depending lugs 64 on the bars 52. The forward ends of the bars 15 62 are recessed as explained of the bars 52 for interlockingly supporting a plate member 65 like the plate 59, and in the manner as above described of the latter.

It will be understood from the above description that the plates 59 and 65 are designed to be supported by, and interlocked with, the bars with which they are associated, and by merely dropping them into place; these plates being of such weight as to ensure against their displacement 25 from interlocked relation with the bars in the operation of the feeding mechanism.

The sections 46 are thus connected together for simultaneous reciprocation to effect the feeding of the coal supplied thereto as hereinafter described, through the coking chamber 44, by power applied to the rack-portions of the bars 52.

The feed mechanism also comprises a fuel-hopper 66 and a trough member 67 located above the bars 52 and extending lengthwise of the latter and provided with a rear wall 68 containing an opening 69 and forming a continuation of the rear wall of the hopper. The opposite side walls of the trough member 67 which extends partly into the coking chamber are formed of lower wall portions 70 and upper outwardly-offset wall-portions 71 providing therebetween, substantially horizontal portions 72 forming ledges.

The bottom 73 of the hopper 66 which extends crosswise of the trough 67 and at opposite sides 45 thereof as shown is of rounded trough-like form and extends substantially to the bottom of the trough 67, the side walls of the latter being cut away as represented at 74 and the hopper-bottom cut away at the portion thereof directly above the trough 67 whereby the trough portions of the hopper-bottom open into the trough 67.

The feeding mechanism now being described 50 also comprises a plunger 75 located, and reciprocable, in the trough 67 between the side-wall portions 70 of the latter, this plunger being of substantially the same height as the wall portions 70 and shown as formed of a portion 76 of inverted U-shape in section secured at its rear end to the yoke 54. The front edge of the portion 76 terminates in a depending flange 77, and projecting forwardly therefrom is a pair of horizontally spaced brongs 78.

The plunger 75 is provided for the purpose of 55 intermittently feeding the fuel from the hopper 66 to the feed devices in the coking chamber and as a means for regulating the amount of fuel fed upon each reciprocation of the plunger, the yoke bars 52 are provided with longitudinal series of holes 79 at which the yoke 54 may be secured to the bars 52 by the bolts 79.

The mechanism also comprises a check-gate 80 60 shown as in the form of a plate pivoted at its upper end, as represented at 81, to a stationary part of the structure, the gate 80 which inclines downwardly and forwardly being of a width sub-

stantially equal to the width of the trough 67 between its upper wall portions 71 and bearing at its lower, forward, edge on the ledges 72.

In the operation of the apparatus, as herein-after described, the coal fed by the plunger passes beneath the gate 80 which latter is made of such weight that its resistance to upward movement is greater than the friction of the coal on the top of the plunger.

10 The plunger 75 and the feed-sections 46 are reciprocated simultaneously by mechanism comprising a pair of gear segments 84 meshing with the rack portions of the bars 52 and rigid on a shaft 85 journalled in the side walls of a bracket-box 86 secured to the casing of the furnace, the 15 box 86 also supporting the trough in which the plunger operates.

The shaft 85 is provided with an arm 87 rigid therewith and pivotally connected at its outer end as represented at 88 with the upper end of a link 20 89, the lower end of which is pivotally connected with a crank pin 90 on a disk 91 rigid on the shaft 43, the disk 91 containing a series of openings 92^a disposed at different distances from the shaft 43 to selectively receive the pin 90 for varying 25 the throw of the link 89.

The trough-forming bottom of the hopper 66 is equipped with agitating means shown as in the form of a shaft 82 journalled in the ends of the trough 73 and equipped with sections 83 of relatively large coil-springs positioned on the shaft 82 as shown so that when the latter is rotated in one direction the spiral sections 83 will operate to exert force on the fuel in the hopper tending to move the fuel from the ends toward trough 67. 35

In the arrangement shown means operatively connected with the link 89 are provided for rotating the spiral agitator in the hopper, the means shown comprising an arm 92 rigid on the shaft 85, a link 93 pivotally connected at its lower end, as 40 represented at 94, to the arm 92 and at its upper end, as represented at 95, to a lever 96 journalled on the shaft 82 and provided with a pivoted pawl 97 cooperating with a ratchet-wheel 98 rigid on the shaft 82, whereby rocking movement of the 45 lever 96 is converted into unidirectional rotary movement of the shaft 82.

It will be understood from the foregoing that rotation of the shaft 43 operates to simultaneously oscillate the gear segments 36 and 64 for 50 reciprocating the grate-members 30, the feed-mechanism sections 46, and the plunger 75 and rotating the agitator device in the bottom of the hopper.

The mechanism for rotating the shaft 43 may 55 be of any desirable construction. That shown is in the form of a fluid-pressure-operated piston and cylinder mechanism represented at 99, the cylinder of which is represented at 100, and may be of any suitable construction, it having a valve 60 mechanism the casing of which is represented at 101 and the stem of the valve at 102 which serves in oscillating to control the inlet of fluid pressure to the opposite ends of the cylinder 100 and the exhaust therefrom, for effecting reciprocation of 65 the piston (not shown) therein which is provided with a piston rod 103.

The piston rod 103 is shown as carrying a member 104 of angle shape, the lower horizontal arm 105 of which is provided with a pair of 70 spaced pins 106 between which the upper end of an arm 107 fixed on a rock-shaft 108, extends. The shaft 108 is journalled in the sides of a casing 109 and has secured thereto a pair of spaced disks 110 (Figs. 8 and 9) equipped with pawls 111 and 75

112 pivoted thereto at 113 and 114, respectively. The pawls 111 and 112 are provided for cooperation with a ratchet-wheel 115 located within the casing 109 and fixed on the shaft 43 journalled in the sides of the casing 109, the ends of the shaft 43 being provided with the disks 42 and 91 as above set forth.

It will be understood from the foregoing that by reason of the provision of the pawl-and-ratchet mechanism just described, the oscillatory movement of the shaft 108, produced by the reciprocations of the piston of the mechanism 99, is converted into rotary movement of the shaft 43, for oscillating the gear segments 36 and 84 and actuating the agitator mechanism, by reason of the above described connections therebetween.

In the arrangement shown the valve device for reversing the flow of fluid pressure into the ends of the cylinder 100 and exhausting the spent fluid therefrom, is automatically operated at substantially the ends of the piston strokes, through the medium of a slide-bar 116 provided with stops 117 spaced apart and located at opposite sides of an arm 118 secured to the upper end of the valve-stem 102, coil springs 119 being interposed between the stops 117 and the arm 118. The slide-rod 116 is also provided with spaced-apart tappets 120, the upwardly extending arm 104a of the member 104 being positioned between these tappets and cooperating therewith to effect the shifting of the rod 116 for controlling the position of the valve mechanism, as will be readily understood. As the piston nears the limit of its movement to the left in Fig. 1 the arm 104a strikes the left-hand tappet 120 turning the valve stem 102 to permit actuating fluid to enter the cylinder 100 at the left-hand end thereof in Fig. 1 and the exhaust pressure to exhaust from the opposite end of the cylinder; and as the piston nears the limit of its movement to the right in Fig. 1 the arm 104a strikes the right-hand tappet 120 to open the right-hand end of the cylinder 100 to the force of fluid pressure and open the opposite end of the cylinder to exhaust.

In the operation of the mechanism, the movement of the plunger 75 to the right in Fig. 1 permits coal to drop onto the bottom of the trough 67 in front of the flange 71 of the plunger and between the prongs 75a, and in its movement to the left in Fig. 1 advances in the trough for discharge upon the feed mechanism in the coking chamber; the coal deposited in the trough from the hopper, it being understood that in the mechanism as shown, and preferably, the pusher portion 77 of the plunger does not move to the left in Fig. 1 beyond the lower edge of the plate 80. The coal thus pushed beyond the inner end of the trough 67 falls upon the upper feeder section 46 which latter in its reciprocations feeds the coal upon and along the upper section 45 from which it discharges to the lower section 46 and is thence fed along and from the lower section 45 from which the fuel drops upon the combined grate and feed mechanism at the bottom of the combustion chamber.

It will be understood from the foregoing that in the movement of the fuel along the bottom of the coking chamber 44 the coal is subjected to the heat from the fire bed on the grate at the bottom of the combustion chamber, causing the coal to become heated with the result of drying the coal and at least partially coking it, the finer particles of coal dropping through the apertures 48 and upon the hot fire bed below, and, being in dried and heated condition, these finer par-

ticles readily ignite, very much the same as in the case of gas, with almost complete combustion.

The coal in passing through the coking chamber gives off more or less of the volatile matter therein which, together with air entering this chamber at the rear end thereof which becomes heated in this chamber, travels, under the action of the draft in the stack, along the coking chamber to the front end thereof and thence into the combustion chamber above the fire bed where it will be burned without waste or smoke.

The coal which is thus delivered to the grate sections in the combustion chamber is in dried and at least partially coked condition thereby eliminating the production of smoke and ensuring practically complete combustion of the coal supplied to the furnace.

The provision of the check gate as above described causes the apparatus to present a relatively small throat portion through which the coal is fed to the coking chamber whereby a regular feed of comparatively small quantities of fuel, regardless of the head of coal in the hopper may be effected, it being noted that the carrying of the coal on the top of the plunger into the furnace is prevented.

The feature of pivoting the check gate as stated is of great advantage inasmuch as provision is thereby made for permitting occasional large lumps of coal contained in the body thereof to be fed to the coking chamber without choking the opening or subjecting the mechanism to undue stresses.

The check gate also serves to ensure the forming of a coal-seal preventing the escape of smoke and gases into the room in which the furnace is located should the mechanism continue to operate after the hopper 66 has been emptied, inasmuch as there will always be a residue of coal in front of the feed portion 77 of the plunger and on the top of the latter which will not feed out and which residual body of coal, in conjunction with the check gate 89, closes the furnace against the escape of smoke and gas.

The provision of the prongs 75a on the plunger 75 is of advantage as they prevent the baking and building up on the plunger of the tars in the fuel when of the low volatile kind, which baking or building up seriously interferes with the regularity of feed and requires greater power for operating the feed mechanism. Furthermore, the prongs referred to operate to avoid the exerting of pressure against the side walls of the trough 67 in the feeding operation with the result of reducing the power required for operating the feed mechanism and minimizing the "bunching" of the coal ahead of the plunger with the result of insuring more nearly perfect regulable feed.

Apparatus constructed in accordance with my invention is of special value for so-called domestic use where the amount of coal required to be fed at intervals is relatively small, the cost of such structures must be kept low, and the same be operated with the minimum of power consumption.

The agitator, the spiral sections 83 of which are preferably of spring steel, is not only of advantage because of its capability of turning freely through the coal when the hopper is full, as compared with the resistance which would be afforded by a solid screw, and its capability of overcoming the tendency of the coal when wet or dirty to pack and hang, by breaking up the body of material, but also as it serves as a screw con-

veyor to feed the coal to the plunger when the fuel supply in the hopper is low.

By providing the pivot plate 121 and the stationary plate portion 124 associated therewith as stated, the fire bed of the grate is caused, by the resistance offered by the plate 124, to bunch up at the rear portion of the fire bed against the plate 121, forming a thicker bed at this point than otherwise would be produced; the pushing action of the movable grate sections 30 being horizontal and the plate 124 presenting frictional resistance to the sliding of the fire bed across it, the partially burned out coals are crowded on top of the fire bed at this point by the movement of the rearwardmost one of the grate sections 30 while the forward grate sections push the ashes, clinkers, and such other non-combustible masses, such as tin cans, broken glass, and crockery, which may have been thrown into the furnace, against the plate 121 which swings rearwardly and permits the ashes, clinkers, and such masses to drop into the ash pan below; thus the fuel is entirely consumed before being dumped into the pit and fire bed is rendered self-cleaning. The bunching of the fire bed against the plate 121 also serves to effectually seal the cleansing spaces at the ends of the plate 121 thereby aiding the draft through the grate.

While I have illustrated and described a particular construction embodying my invention, I do not wish to be understood as intending to limit it thereto, as the same may be variously modified and altered without departing from the spirit of my invention.

What I claim as new, and desire to secure by Letters Patent, is:

1. In stoker mechanism, the combination of a container for the coal having an outlet portion, a trough, the upper portions of the side walls of said trough being laterally offset, a feed member reciprocable in the lower portion of said trough and operative to feed the coal in said trough, and an upwardly yieldable member extending into the upper portion of said trough normally resting upon the shoulders of said offset and against which the coal fed by said first-named member moves, for the purpose set forth.

2. In stoker mechanism, the combination of a container for the coal having an outlet portion, a trough, the upper portions of the side walls of said trough being laterally offset, a feed member reciprocable in the lower portion of said trough and operative to feed the coal in said trough, and a check-gate for the coal fed by said member comprising a hinged plate extending in the upper portion of said trough, inclining downwardly in the direction in which the coal is fed and resting upon the shoulders of said offset.

3. In stoker mechanism, the combination of a container for the coal having an outlet portion, a trough, the upper portions of the side walls of said trough being laterally outwardly offset and presenting ledges at the opposite sides of the trough between the upper and lower edges thereof, a feed member reciprocable in the lower portion of said trough and operative to feed the coal in said trough, and an upwardly yieldable member extending into the upper portion of said trough and normally bearing on said ledges and against which the coal fed by said first-named member moves, for the purpose set forth.

4. In stoker mechanism, the combination of a container for the coal having an outlet portion, a trough the upper side walls of which are laterally offset, a feed member reciprocable in the lower portion of said trough and operative to feed coal in said trough, and an upwardly yieldable member extending into the portion of said trough above said offset portions and against which the coal fed by said first named member moves and of substantially the same length as the width of the upper portion of said trough, said first-named member having spaced apart prongs extending forwardly therefrom and in the lower portion of said trough and between which the coal becomes positioned.

5. In stoker mechanism, the combination of a container for the coal having an outlet portion, a trough the upper side walls of which are laterally offset, a feed member reciprocable in the lower portion of said trough and operative to feed coal in said trough, and an upwardly yieldable member extending into the portion of said trough above said offset portions and against which the coal fed by said first-named member moves and of substantially the same length as the width of the upper portion of said trough and normally resting upon the shoulders of said offsets.

6. In stoker mechanism, the combination of a container for the coal having an outlet portion, a trough the upper side walls of which are laterally offset, a feed member reciprocable in the lower portion of said trough and operative to feed coal in said trough, and an upwardly yieldable member extending into the portion of said trough above said offset portions and against which the coal fed by said first-named member moves and of substantially the same length as the width of the upper portion of said trough and normally resting upon the shoulders of said offsets, said first-named member having spaced apart prongs extending forwardly therefrom and in the lower portion of said trough and between which the coal becomes positioned.

ORIN KELLY.
